SURGICAL BOOT

Frances E. Gogerty, Balboa Island, Calif.

Application January 10, 1948, Serial No. 1,602

6 Claims. (Cl. 36—8.5)

1

My invention relates to surgical covering devices and particularly to a shoe or boot adapted to be worn over the lower extremity of a plaster leg and foot cast to provide a covering therefor.

In situations where a plaster cast must be worn on the foot and ankle of a person, the lower extremity or foot of the cast is usually left exposed and thus unprotected against cold temperatures and inclement weather. For this reason, the cast is apt to become wet and cold and, because it has fair thermal and moisture conductivity, the enclosed foot of the person is accordingly subjected to such adverse conditions with the result that much discomfort is experienced by the wearer. Moreover, such casts have an extremely awkward, bulky and displeasing appearance and for this reason are regarded with disfavor.

It is the primary object of my invention to avoid such a condition by providing a surgical shoe or boot which can be worn over the lower extremity of a leg cast as a protective covering therefor and which is capable of effectively shielding the cast against extreme temperature changes and moisture and, in addition, adapted to conceal the foot cast to avoid an undesirable appearance.

Another object is to provide a boot of the type indicated which can be conveniently applied to and removed from the cast so that it can be worn only outdoors, if desired.

Another object is to provide a boot of the type specified, having a rear or heel portion which can be readily opened to permit the boot to be applied to the foot of the cast by sliding it thereover, and provided with wings or straps formed as extensions of the sides of the boot and adapted to be crossed at the rear of the boot to close the same, said straps being brought around the front of the ankle portion and secured together, preferably by snap-fastener means, to retain the boot in place on the cast.

Another object is to provide a surgical boot in which the straps have a plurality of the snap-fasteners, any of which can be selectively employed, so as to adapt the boot for use on leg casts of different ankle dimensions.

Further objects of my invention will be apparent from the following description and from the drawing, which is intended for the purpose of illustration only, and in which:

Fig. 1 is a perspective view of my surgical boot, showing it in place on the foot portion of a leg cast, prior to being fastened thereon;

Fig. 2 is a rear perspective view of the boot, illustrating the manner in which the straps are crossed, prior to being secured together; and

Fig. 3 is a view similar to Fig. 1 but showing the

2

straps connected at the front of the ankle portion of the leg cast to retain the boot on the cast.

Referring to the drawing in detail, the surgical boot 5 is made in the general form of a shoe, the boot having a sole portion 6, and an upper or vamp 7 which extends upwardly to provide an ankle portion 8. The boot may be made from any suitable flexible material which preferably possesses thermal insulating qualities and is substantially impervious to moisture. The boot 5 may be fabricated from several parts sewed together or otherwise joined as shown in Fig. 1. Preferably, the boot 5 includes an intermediate portion or strip 29 which is made from fabric and cut on the bias so that it is capable of stretching both longitudinally and transversely. By this provision, the boot 5 is made adjustable so that it will conform to either right or left-hand foot casts of large and small sizes. It is also desirable that the sole portion 6 be made from a material such as canvas, which is non-raveling and non-stretching so that its rear portion can be slit to adapt the boot to be placed over a foot cast in which a projecting metal loop or "walker" is used as a support for the heel, the walker then extending through the slit to rest upon the ground.

It will be noted, by reference to Fig. 1, that the opposite sides of the ankle portion 8 of the boot 5 are extended rearwardly in wing-like straps 10 and 11, thereby leaving an opening 12 at the rear of the boot through which the foot of the leg cast 13 can be inserted into the boot. The straps 10 and 11 preferably have curved lower edges 14 and it will be observed that the strap 11 is slightly narrower throughout its major portion than the strap 10. The strap 10 is provided with an elongated slot or opening 15 through which the strap 11 can be passed so as to cross the straps at the rear of the boot and thus close the opening 12 after the boot has been applied to the foot of the leg cast.

The free ends of the straps 10 and 11 are adapted to be joined together at the front of the ankle portion 8 by suitable fastening means, the present drawing showing a series of snap-fasteners for this purpose. The male snap-fastener elements 18 are secured to the strap 11, adjacent its free end, while the female elements 19 are similarly carried at the end of the strap 10. It is apparent that by providing a plurality of the snap-fastener elements 18 and 19, any or all the fasteners may be employed for releasably securing the straps together as shown in Fig. 3, and that by this means the ankle portion 8 can be adjusted in girth to adapt it to encircle the ankle portions of leg casts of different size. It will be noted that by

providing the straps 10 and 11 with curved lower edges, the straps follow the contour of the instep portion of the cast so that a snug fit of the boot on the cast is obtained.

To apply the surgical boot 5 to the foot and ankle of the leg cast 13, the straps 10 and 11 are extended as shown in Fig. 1 so as to provide the opening 12 at the rear of the boot. By inserting the foot of the leg cast 13 through the opening 12 and sliding the boot rearwardly, the boot is readily donned. After the boot 5 has been positioned on the foot of the cast, the end of the strap 11 is passed through the slot 15 of the strap 10 and the two straps drawn apart laterally as shown in Fig. 2 so as to cause them to cross each other and close the opening 12 at the rear of the boot. The free ends of the straps 10 and 11 are then carried around the front of the ankle portion 8, the end of the strap 10 being lapped over the end of the strap 11 and secured thereagainst by merely snapping its fastener elements 19 over the elements 18. Since the opening at the rear of the boot is entirely closed by the crossing straps 10 and 11, the use of adhesive tape or other separate closure means is unnecessary and the placing of the boot on and its removal from the cast is greatly expedited and simplified.

It will be understood that any of the several elements 18 and 19 may be utilized to retain the straps in connected relationship so that a snug fit of the ankle portion 8 around the cast 13 is effected. It is thus seen that the boot 5 can be employed as a covering for the foot and ankle portions of legs casts of different size.

The boot 5 adequately covers the lower extremity of the cast and by constructing the boot from a material having low thermal conductivity and one which is highly impervious to moisture, the cast is protected against extreme temperature changes and rain and snow so that the foot enclosed by the cast is not subjected to such adverse weather conditions and more comfort is experienced. Moreover, the boot adequately conceals the lower extremity of the leg cast and thus eliminates the bulky and awkward appearance of such surgical casts.

While I have herein shown and described the surgical boot as embodied in a preferred construction, by way of example, it will be apparent that various modifications might be made therein without departing from the spirit of the invention. Consequently, I do not wish to be limited in this respect, but desire to be afforded the full scope of the appended claims.

I claim as my invention:

1. A surgical boot adapted to cover a surgical foot and ankle cast, including: a flexible foot portion having a sole including a heel and an upper for enclosing the fore part of the foot section of the cast; and upstanding U-shaped ankle portion having a central part joined to said upper and sides joined to the rearward end of said heel and cooperating with said heel to completely enclose the sides and bottom of the heel section of the cast, said sides of said ankle portions providing between them an opening in the rear of the boot through which the foot and ankle sections of the cast can be inserted; straps forming rearward extensions of the sides of said ankle portion, one of said straps having an aperture therein through which the other strap can pass to adapt the straps to cross each other at the center of the back of the boot so as to close said opening and to encircle the ankle section of the cast with

their free ends overlapping; and interengageable fastening means on said straps adjacent their free ends adapted to adjustably connect said free ends at the front of the ankle section of the cast.

5 2. A surgical boot as defined in claim 1, and including a fabric strip interposed between said sole and said upper, said strip being cut on the bias to adapt it to stretch both longitudinally and transversely so as to permit use of the boot on casts of different sizes and shapes.

10 3. A surgical boot as defined in claim 1, in which said sole is constructed from a non-raveling, non-stretchable material capable of being slit.

15 4. A surgical boot adapted to cover a surgical foot and ankle cast, including: a flexible foot portion having a sole including a heel and an upper for enclosing the fore part of the foot section of the cast; an upstanding U-shaped ankle portion having a central part joined to said upper and sides joined to the rearward end of said heel and cooperating with said heel to completely enclose the sides and bottom of the heel section of the cast, said sides of said ankle portions providing

20 between them an opening in the rear of the boot through which the foot and ankle sections of the cast can be inserted; straps forming rearward extensions of the sides of said foot and ankle portions; one of said straps having an aperture therein through which the other strap can pass to adapt the straps to cross each other at the center of the back of the boot so as to close said opening and to encircle the ankle section of the cast with the free end of one of said straps over-

25 lapping the free end of the other of said straps; and interengageable fastening means on said straps adjacent their free ends adapted to adjustably connect said free ends at the front of the ankle section of the cast.

30 5. A surgical boot as defined in claim 4 in which the lower edges of said straps are curved to adapt them to follow the contour of the instep section of the cast.

35 6. A surgical boot adapted to cover a surgical foot and ankle cast, including: a flexible foot portion having a sole and an upper for enclosing the foot section of the cast; an upstanding ankle portion, said foot and ankle portions having an opening in the rear thereof through which the foot and ankle sections of the cast can be inserted; straps forming rearward extensions of the sides of said foot and ankle portions; one of said straps having a vertical slot therein through which the other strap can pass to adapt the straps to cross

40 each other at the center of the back of the boot so as to close said opening and to encircle the ankle section of the cast with their free ends over-lapping, said straps having curved lower edges adapted to follow the contour of the instep section of the cast; and interengageable snap-fastener elements on said straps adjacent their free ends adapted to be selectively engaged so as to adjustably connect said free ends at the front of the ankle section of the cast.
